UNITED STATES PATENT OFFICE.

HANNIBAL GOODWIN, OF NEWARK, NEW JERSEY; REBECCA GOODWIN EXECUTRIX OF SAID HANNIBAL GOODWIN, DECEASED.

CAMERA.

SPECIFICATION forming part of Letters Patent No. 729,325, dated May 26, 1903.

Application filed April 22, 1899. Serial No. 714,070. (No model.)

To all whom it may concern:

Be it known that I, HANNIBAL GOODWIN, a citizen of the United States, residing at Newark, in the county of Essex and State of New Jersey, have invented certain new and useful Improvements in Cameras; and I do hereby declare the following to be a full, clear, and exact description of the invention, such as will enable others skilled in the art to which it appertains to make and use the same, reference being had to the accompanying drawings, and to letters of reference marked thereon, which form a part of this specification.

This invention relates to that class of photographic cameras in which provision is made for the manipulation of the sensitive films individually from the outside of said camera, the objects of the present improvements being to facilitate the operation of loading the camera, to reduce the cost of construction, and secure other advantages and results, some of which may be referred to hereinafter in connection with the description of the working parts.

The invention consists in the improved photographic camera and in the arrangements and combinations of parts of the same, all substantially as will be hereinafter set forth, and finally embraced in the clauses of the claim.

Referring to the accompanying drawings, in which like letters of reference indicate corresponding parts in each of the several figures, Figure 1 is a plan of the camera with the top plate or cover removed to show the arrangement of parts within more clearly. Fig. 2 is a vertical section of the same, taken at line x . Fig. 3 is a plan of a film-holder of peculiar construction adapted to be inserted in the camera-box. Fig. 4 is a section of the same on line x' , and Fig. 5 is a section on line x^2 . Fig. 6 is a plan of a portion of the holder in detail, and Fig. 7 is a perspective view of one of a series or collection of cut films adapted to be arranged in said holder.

In said drawings, a indicates a suitable camera-box, having the usual aperture a' at the front, through which the light enters in its passage to the lens, and a partition a^3 , to which may be attached the lens-box b , or said box or the lens therein may be arranged in

any other manner in connection with the attachments commonly employed in photographic cameras, such as the shutters and means for controlling the quantity of light 55 entering to the lens.

The front board a^4 and partition a^3 are each open at the bottom or terminate short of the bottom board a^5 of the box, as indicated in Fig. 2, to form passages for the films and a 60 portion or section of the film-holder, as hereinafter described, and at the rear the side boards a^6 are vertically grooved, as at $a^7 a^7$, to form slideways for another portion of the said film-holder. At the top the box is provided with a removable top board or cover a^8 , 65 suitably formed at the edges to make joints with the body of the box impermeable to light.

The film-holder is formed in chambered sections or parts $c' c^2$, hinged together at d , 70 so that the sections may be turned on the hinge-pins from the relation of alinement shown in Figs. 3 and 4, at which they may be laid out upon a table, and thus easily manipulated in loading, to the right-angular relation shown in Fig. 2, in which latter relation they are prepared for picture-taking 75 within the camera.

The part or section c' , adapted to stand vertically in the slideways a^7 of the camera-box, comprises a body-plate c^3 , bent at its opposite sides at right angles to its own body, as at $c^4 c^4$ in Fig. 5, and again bent outwardly parallel with said body to form flanges $c^5 c^5$, a pressure-plate c^6 , arranged between the 85 sides $c^4 c^4$, and a sliding open diaphragm c^7 , having returned edges c^8 , adapted to receive the flanges $c^5 c^5$, the said flanges forming slideways for said open diaphragm and the returned side parts c^8 of the open diaphragm 90 serving as slide-tongues to enter the slideways a^7 of the camera-box. The slide-tongues may be applied to the camera-box and the film-holder be correspondingly modified as a reversal of construction. The open diaphragm may be constructed to operate other than to slide upon the body of the section. 95

The pressure-plate c^6 at its back is provided with bowed springs $c^9 c^9$, by means of which the said pressure-plate is forced forward 100 against the back of the series or collection of films and the latter are pressed forward

against the rear side of the open diaphragm c^7 . The back of the body-plate c^3 is provided with openings c^{11} c^{11} , through which the springs may project, as indicated in Figs. 2 5 and 4, to bear against the back board a^9 of the box a when pressing the plate c^6 and the films in front thereof forward against the open diaphragm c^7 , forming a part of the section c' .

10 The section c^2 , hinged to the section c' , comprises a box-like receptacle c^{12} , open at the top and at opposite ends. By means of the pivotal connection of the two sections said sections may change in their angular relation 15 to one another, and this not only facilitates taking the holder out of the camera and replacing it, as hereinafter described, but also enables the two sections to be brought into the same plane for the insertion of a fresh 20 package or collection of films. The open top permits the arrangement of the films in place when loading and is provided with a cover c^{13} , closing said open top to form a dark chamber within. The said cover is provided with 25 suitable catches c^{14} , adapted to engage coöperating catch projections c^{14} at the opposite sides of the receptacle, whereby said cover is held with sufficient security in place. At its forward end said cover c^{13} is provided with a 30 partition or plate c^{15} , adapted to reduce the depth of the dark chamber and press the collection of cut films together, and thus prevent an entrance of light through the forward end opening of the holder-section c^2 . The 35 contracted mouth of the dark chamber of said holder-section c^2 is intended to accommodate a given quantity or number of sheets of the supports or the paper portions of the film, permitting an outpassage thereof, but 40 preventing the outpassage of the double portions of the films where the flexible celluloid film is attached to the face of the supporting paper. In other words, the contracted passage c^{18} is formed to receive a definite number 45 of the extensions of the supporting portions of the films only, and thus prevent the outpassage of the applied sensitive films when the latter are drawn into the dark chamber of the section c^2 , as hereinafter described. 50 Said forward end of the cover is also provided with a stop flange or projection c^{16} to press against the inner side of the box and prevent possible free longitudinal play and close the interior of the camera against an entrance of 55 light. A lip c^{17} or extension of the partition c^{15} preferably extends into the front opening at or near the bottom of the box to hold the part or section c^2 of the film-holder down against the bottom board. 60 The open hinged end of the part c^2 is of the same width interiorly and coincides with the open lower end of the part or section c' , so that the films may pass freely from the said part or section c' into the part or section c^2 when the film-holder is arranged in its angular form or relation within the camera-box, as shown in Fig. 2.

The lower edge of the open diaphragm c^7 is preferably curved outward, as shown in Fig. 2, providing a convex bearing over which the films may be bent without injury to the sensitive portions in the act of drawing the same into the dark chamber c^{20} within the section or part c^2 of the film-holder.

At or near the angle or hinge joint between the parts or sections c' and c^2 of said holder is arranged a stop pin or pins f . This or these are preferably rigidly mounted upon the body portion c^3 of the part or section c' of the film-holder, terminating at their projecting ends 80 a little short of the open diaphragm c^7 , a sufficient space being formed between to receive the spring and permit the passage between the spring and stop pin or pins of a single celluloidal film with its paper support. At their upper ends said springs g are suitably attached to the rear side of the open diaphragm c^7 , and at their lower free ends said springs are adapted to press normally against the projecting ends of the stop-pins f to prevent premature withdrawal of the film. The said stop-pins f are arranged at or approximately at right angles to the planes of the portions of the films which stand erect in the part or section c' of the camera, and thus said erect portions 95 bear upon said pins when stress is brought upon the rear films due to the downdrawing of the front film of the series into the dark chamber after the sensitive portion thereof has been photographically light-impressed. 100

In connection with this specification of the purpose of said stop-pins it is important to mention that by the bending of the package of films to a comparatively sharp angle at the junction of the two sections c' and c^2 each 105 front or foremost film of the series can be withdrawn from section c' without withdrawing or disturbing the next film or series of films immediately in its rear, and thus on account of the aforesaid angular formation of the package the remaining package can be maintained in position without the aid of stop-pins; but I prefer to employ the said stop-pins, as it more positively insures a withdrawal of but one film at a time. 115

The spring or springs g is limited in its movement away from the extremity of the stop-pin by the open diaphragm.

In Fig. 3 the employment of the two independent springs g is indicated, and in Fig. 6 120 a single piece comprises the spring, which spring in this case resembles a metallic frame.

The parts or sections c' c^2 of the film-holder are of substantially uniform width interiorly, and thus the portion k' of the film k , Fig. 7, 125 forming a backing for the celluloidal portion k^3 having the sensitive coating, when drawn into the dark chamber of the part c^2 will extend from side to side of the chamber within the part c^2 , thus reducing the liability of fogging due to the formation of open or unfilled crevices in the dark chamber through which the light might pass.

In the construction of the cut film k I em-

ploy an opaque support comprising a sheet of paper $k' k^2$, a separate and independent sheet for each celluloideal film k^3 , having the photographically sensitive coating. This sheet $k' k^2$ is of a length sufficient to extend from the upper end of the film-holder downward and through the section or portion a^2 thereof and thence out from the film-holder and camera to a point where it can be conveniently grasped by the hand of the operator, as shown in Fig. 2. The portion k' of the support beneath or behind the sensitive film k^3 I have termed the "backing." The part k^2 extending from the backing I may term the "handle extension." Near one end of each of the said sheets $k' k^2$ is fastened by cement or other suitable means the said sensitive film k^3 .

At or near the lower ends of the films k^3 the same are perforated, as at k^4 , to receive the stop pin or pins f , the perforations k^4 extending through both the films and the paper supports or backing.

Forward from the combined film k^3 and paper backing k' in the handle extension k^2 is formed a hole or a series of holes k^5 or other indicating marks adapted to serve as an indicator or indicators in the act of withdrawing the film k , the said indicating marks or holes being so related to the paper handle extension k^2 as that when said marks appear to view at the outside of the camera in the act of withdrawing the film the operator is made aware of the fact that the sensitive portion k^3 is properly within the dark chamber protected from light and that further withdrawing is unnecessary.

The extensions k^2 forward from the sensitive celluloideal portions k^3 may be also marked numerically or otherwise by printing, perforations, or otherwise to indicate the number of each individual film in the series.

Outside the camera-box the front board is provided with a shutter m , suitably arranged in slideways n , adapted to press the finger extensions of the series together to prevent the possible entrance of light to fog the films and adapted to act as a blade for severing each film when sufficiently withdrawn after each exposure has been made.

In operating the device, the holder being properly loaded by first removing the covers from the parts $c' c^2$ while the same is detached from the camera, then arranging the films k in place therein, so that their handle extensions at the extremities project from the holder, as shown in Fig. 2, and the sensitive portions k^3 will face toward the opening of the diaphragm, and finally applying the said covers, I first insert the part c^2 within the camera-box and then the part c' , the latter being arranged in the slideways a^7 and pushed downward into proper vertical position. The sections are formed so that the part c^2 at its forward end will enter the opening a^2 as the part c' is pressed downward. The cover a^8 is then applied to the box and the camera is ready

for service. The sensitive film at the front of the series having been exposed to light through the lens, the uppermost finger extension projecting out from the camera is drawn upon and the backing thereof is drawn away from the next film of the series at the bend in the series and is drawn from the stop-pins, so that it is free to be drawn downward. The sensitive celluloideal portion and its backing are finally drawn into the dark chamber, when the marks or perforations k^5 in or on the extension will appear to view and the drawing will be discontinued. The portion of the film thus withdrawn from the camera-box is torn or cut off by pressing it against the aforesaid shutter-blade. Inasmuch as a hundred films, more or less, may be loaded within the holder, the need for daylight filling or loading is virtually avoided.

While I have described the invention, in many instances using positive terms, I am aware that various changes and modifications may be made other than have been referred to in the construction and arrangements of parts without departing from the spirit or scope of the invention, and I do not wish to be understood as limiting myself by the said positive descriptive terms employed excepting as the state of the art may require.

Having thus described the invention, what I claim as new is—

1. In a camera, a holder for cut films, said films each having a sensitive portion and a non-sensitive extension, said holder comprising a receptacle for the sensitive portions of the films, and a chambered part for the non-sensitive portions of the films and into which the sensitive portions are adapted to be drawn after exposure, said receptacle and chambered part being disposed at an angle to each other, but hinged together and adapted to be removed from the camera as a unitary part, substantially as set forth.

2. In a camera, the combination with the part c' , of the holder having stop-pins f , of a hinged part c^2 , having a dark chamber, substantially as set forth.

3. In a camera, a holder for cut films, said films each having a sensitive portion and a non-sensitive extension, said holder comprising a receptacle with an open front for the sensitive portions, and having stop-pins and a spring or springs tending to hold the films on said stop-pins, and a dark chamber through which the non-sensitive extensions of the unexposed films extend and into which the sensitive portions are drawn by said extension after exposure, substantially as set forth.

4. In a camera, the pellicle or film-holder, comprising a part or receptacle for the unimpressed films, having an open front, a pressure-plate, stops or holders for holding the films in proper relation to the open front, and a spring or springs adapted to engage said stops and coöperate therewith in holding the films in place and a part or receptacle for the light-impressed films in open communication

with the first said part or receptacle and adapted to be withdrawn from the camera-box therewith, substantially as set forth.

5. In a camera, a holder for cut films, said films each having a sensitive portion and a non-sensitive extension, said holder being separable from the camera, and composed of parts hinged together to permit of its insertion and removal, one of said parts being adapted to contain the sensitive portions of the unexposed films and having an open front for their exposure, and the other part forming a dark chamber in open communication with the first-mentioned part at their adjacent ends and into which the sensitive portions are adapted to be drawn by their non-sensitive extension after exposure, substantially as set forth.

6. In a camera, a holder for cut films, said films each having a sensitive portion and a non-sensitive extension, said holder comprising parts c' , c^2 , hinged together and one forming a receptacle for the sensitive portions of the films and the other a chamber for the non-sensitive extensions, and said parts turning freely on their hinge-joint when removed from the camera but being held in fixed relative position in the camera, substantially as set forth.

30 7. In a holder for cut films having finger extensions, the combination of a receptacle for the films, a pin against which said films rest edgewise, and a spring pressing on the ends of said pin, but adapted to permit the foremost film to pass between itself and the pin when draft is applied to its finger extension, substantially as set forth.

8. In a camera, a removable holder for cut films, comprising hinged or pivoted sections held in fixed relation to each other when in place in the camera but adapted to change their angular relation during removal or insertion, substantially as set forth.

9. A holder for cut films having a sensitive portion and a non-sensitive extension, said holder comprising two chambers one adapted to contain said sensitive portions of the films and the other to inclose the non-sensitive extensions and into which the sensitive portions are drawn after exposure, said chambers being hinged together and permanently open to each other at their contiguous ends, whereby

the holder can be filled with the chambers extended into alinement and afterward be bent out of said alinement, substantially as set forth.

10. A holder for cut films having finger extensions, said holder consisting of two chambers hinged together and open to each other at their contiguous ends, the unexposed films lying in one chamber and their finger extensions extending into the other chamber and projecting therefrom, an exposure-opening in the side of the chamber for the sensitive portions of the films, and means in said chamber for holding stationary all said films except the front one when said front film is drawn into the other chamber by its finger extension, substantially as set forth.

11. A holder for cut films having extensions for their manipulation, said holder comprising chambers hinged together at their ends and adapted to be extended into alinement, said chambers being open to each other at their hinged ends, and one chamber having a removable side permitting the insertion of a package of films and providing means for manipulating the films, while the other chamber has means for detaining the films, substantially as set forth.

12. A holder for cut films, comprising hinged sections open to each other at their contiguous ends and forming together a chamber for the films, one section having near the hinge-point a stop or stops for the films and at the front ends of said stop or stops a rounded bearing over which the films may bend in passing from one section to the other, substantially as set forth.

13. A holder for cut films having finger extensions said holder comprising sections hinged together and open to each other at their contiguous ends, one section being adapted to receive the sensitive portions of the films and the other the finger extensions, and the whole forming a jointed holder, substantially as set forth.

In testimony that I claim the foregoing I have hereunto set my hand this 15th day of April, 1899.

HANNIBAL GOODWIN.

Witnesses:
